UNITED STATES PATENT OFFICE

2,246,454

ATTACHMENT FOR CARDING MACHINES

Isaac P. Peloquin, Lowell, Mass., assignor to Boott
Mills, Lowell, Mass.

Application November 27, 1939, Serial No. 306,385

3 Claims. (Cl. 19—150)

This invention relates to carding machines, and more particularly for providing a device in the form of an attachment to be used in association with a calendar roll or calendar mechanism for parallelizing the fibers in a card sliver.

An object of this invention is to provide an attachment for parallelizing the fibers in a card sliver which may be mounted on the present structure of a carding machine and may if desired, be positioned either on the input or the output side of the calendar roll, between the doffer cylinder and the calendar roll, between the calendar roll and the coiler mechanism, within the coiler head, or at any point from where the card web leaves the doffer up to the point where the card web or sliver enters the receiving can.

Another object of this invention is to provide an attachment of this kind which when mounted on the carding machine will eliminate the subsequent processing of the sliver through a drawing frame.

A still further object of this invention is to provide an attachment of this kind which includes pairs of rolls, a slidable mounting for the rolls and a weight connected to certain of the rolls for placing the sliver under the desired pressure as it passes through the rolls.

To the foregoing objects and to others which may hereinafter appear, the invention consists of the novel construction, combination and arrangement of parts as will be more specifically referred to and illustrated in the accompanying drawings, wherein is shown an embodiment of this invention, but it is to be understood that changes, modifications and variations may be resorted to which fall within the scope of the invention as claimed.

In the drawings:

Figure 1 is a top plan of an attachment constructed according to an embodiment of this invention, the attachment being shown mounted on a carding machine which is shown in fragmentary form.

Figure 2 is a sectional view partly in detail taken on the line 2—2 of Figure 1.

Figure 3 is a fragmentary end elevation of the attachment.

Figure 4 is a fragmentary sectional view taken on the line 4—4 of Figure 1, and

Figure 5 is a fragmentary sectional view taken on the line 5—5 of Figure 1.

Referring to the drawings, the numeral 10 designates generally the frame of a carding machine wherein a pair of calendar rolls 11 are rotatably mounted. The rolls 11 are mounted on

shafts 12 and 13 which are journaled in the frame structure 10 and the shaft 12 is preferably extended laterally and is provided with a gear 14 which is fixed thereon. The gear 14 meshes with a gear 15 mounted on a shaft 16 which may be connected to a suitable driving means or other part of the card machine and whereby the desired rotary movement is provided for the calendar rolls 11.

In order to provide a means whereby the sliver of cotton passing between the calendar rolls 11 may have the fibers thereof made parallel, I have provided a parallelizing attachment including a pair of substantially U-shaped brackets generally designated at 17. The brackets 17 have one leg 18 thereof disposed in a horizontal position for engaging on a horizontal frame part 19 which is formed as part of the frame structure 10. The leg 18 is secured to the supporting part 19 by fastening devices 20. In the present instance, the bight 21 of the bracket 17 is disposed adjacent the lower calendar roll 11 and the upper leg 22 extends rearwardly and in parallel relation with the lower leg 18. The two brackets 17 are positioned in the present instance, between the calendar rolls 11 and the doffer cylinder.

Each upper leg 22 has a pair of guide members 23 and 24 for bearings mounted thereon. The guide member 23 is provided with a slot or recess 25 opening through the upper end thereof and upper and lower bearing members 26 and 27 respectively are slidable in the slot 25 which forms a guide for the bearing members 26. The guide member 24 is also provided with a guide slot 28 and upper and lower bearing members 29 and 30 are slidable in the guide-way 28. The guide members 23 and 24 may be secured to the upper side of the horizontal leg 22 in any suitable manner. An upper roll 31 is disposed between the two bearing members 23 and is provided at the opposite ends thereof with trunnions or stub shafts 32 which are journaled in the bearing members 26. A second upper roll 33 is disposed forwardly of the first roll 31 and is provided at the opposite ends thereof with trunnions 34 which are journaled in the bearings 29.

A lower forward roll 35 which is provided at one end with a trunnion 36 is positioned below the forward roll 31 and the trunnion 36 is journaled in one bearing 27. A shaft 37 is formed with the roll 35 and extends from the roll 35 opposite from the trunnion 36. A gear 38 is fixed to the shaft 37 and is adapted to mesh with a gear 39 which is mounted on a stub shaft 40 carried by the frame structure 10. A second

or forward roll 41 is disposed below the roll 33 and is provided with a stub shaft or trunnion 42 journaled in one of the bearings 38. A drive shaft 43 is carried by the opposite end of the lower roll 41 and the drive shaft 43 has a gear 44 fixed thereto which meshes with the gear 39. A second gear 45 is mounted on the drive shaft 43 and meshes with a gear 46 carried by a stub shaft 47. The gear 45 also meshes with the gear 14 so that rotation of the calendar rolls 11 will effect rotation of the paralleling rolls 31, 33, 35 and 41. The gear 44 is substantially smaller in diameter than the gear 45 so that the two forward rolls 31 and 35 are rotated at a speed less than the rolls 33 and 41. In this manner there will be a drawing of the fibers which will effect a parallelizing of the fibers prior to the time the sliver enters between the calendar rolls 11.

In order to provide a means whereby the upper or idler rolls 31 and 33 may be held in contacting relation with the sliver and so that the desired pressure may be applied to the sliver, I have provided a pair of saddle members 48 which engage over the trunnions 32 and 34. Each saddle member 48 is provided with an arcuate recess 49 forming a seat to prevent endwise movement of the saddle 48 during the rotation of the idler rolls 31 and 33. A weight 50 is provided for each saddle 48 and the weight 50 is mounted on the lower end of a vertical roll 51. The upper end of the roll 51 is provided with an eye 52 in which the saddle 48 is loosely received.

A trumpet or sliver compressing member 53 is disposed with the reduced end thereof confronting the two rolls 31 and 33 and the flared end of the trumpet 53 is secured to a vertical web or guard 54 which is provided with angularly disposed opposite end portions 55. A base plate 56 extends rearwardly from the web or guard 54 and a plate or flange 57 is secured to the lower end of the web or guard 54 and extends forwardly therefrom being secured by means of a fastening device 58 to the upper leg 22 of a bracket 17. A depending plate or guard 59 is carried by the rear edge of the base plate 56 and coacts with the web or guard 54 in providing a means to prevent the stray ends of fibers from engaging between the parallelizing rolls adjacent the ends of these rolls.

A condensing guide 60 is disposed between the output side of the rolls 33 and 41 and the input side of the calendar rolls 11. This condensing guide 60 is formed of upper and lower frusto-triangular plates 61 which are connected together by end plates 62. The large end of the guide 60 confronts the output sides of the rolls 33 and 41. The guide 60 is supported in the desired position relative to the two rolls 33 and 41 by means of a supporting bar 63 which is secured to the lower plate 61.

In the use and operation of this attachment, the two bracket members 17 are mounted on the frame part 19 by the fastening devices 20. The gear 43 is mounted in a position to mesh with the calendar gear 14 which is commonly known as the carrier element. The rolls 31, 33, 35 and 41 are then mounted in their respective bearings which are slidably mounted within the guide slots 25 and 23 of the bearings 23 and 24. The carding machine is then operated in the usual manner and as the sliver passes from the doffer cylinder into the calendar rolls 11, the sliver will pass through the trumpet 53 and between the first pair of rolls 31 and 33. The lower roll 75

55 is positively driven through the hereinbefore described gear train whereas the upper roll 31 is an idler roll.

The two weights 50 will maintain the upper roll 31 in the desired contacting relation with the sliver as it moves between the two rolls 31 and 33. The gear train is so arranged that the lower forward roll 41 will rotate at a speed greater than the rear roll 33 so as to effect a drawing or pulling on the fibers in the space between the two rolls 33 and 41. This drawing or pulling will have the effect of parallelizing the fibers which will then pass through the condensing guide into the calendar rolls.

The use of an attachment of this kind on a carding machine will make it unnecessary to pass the sliver through a drawing machine, the purpose of which is to make the sliver fibers parallel. It will therefore be apparent that this attachment will eliminate the drawing process which at present is performed by a separate machine. This attachment may be mounted on the present structure of a carding machine without affecting the arrangement of the parts on the machine and at the same time eliminate the subsequent step of making the fibers parallel by the sliver through a drawing process.

What I claim is:

1. In combination in a carding machine, superposed calendar rolls, a frame for revolvably supporting said rolls, driving means for said rolls, and means secured to said frame at the intake end of the machine and disposed in spaced alignment with respect to said rolls for eliminating processing of a sliver through a drawing frame, said means including front and rear idler rolls, a feed roll disposed below the front idler roll, a drawing roll disposed below the rear idler roll, means for driving said drawing roll from a calendar roll, means for driving the feed roll from said drawing roll, a supporting structure common to said idler, feeding and drawing rolls and in which such rolls are slidably mounted, a trumpet secured to said structure intermediate the ends of the latter and having its axis disposed in a plane extending between the idler rolls and said feeding and drawing rolls, a condenser arranged within, extending rearwardly from and connected to said structure in proximity to the top of the latter, and weighting means common to the ends of said idler rolls and depending through said structure.

2. In a carding machine attachment for eliminating the subsequent processing of the sliver through a drawing frame, said attachment comprising a pair of upstanding parallel spaced brackets, means for securing the lower ends of said brackets to the carding machine frame at the intake end of the machine and between a doffing cylinder and the calendar rolls, a front and a rear vertically disposed sidewise aligned bearing guides secured upon the top of each bracket, front and rear upper bearings mounted in said guides, front and rear lower bearings mounted in said guides, front and rear idler rolls carried by said upper bearings, a feed roll carried by said lower front bearings, a drawing roll carried by said rear lower bearings, a vertical support secured upon the front portion of the top of said brackets, a rearwardly directed horizontally disposed trumpet secured to said vertical support, a supporting member arranged between said rear guide members between the upper and lower ends of the latter, a horizontally disposed condenser mounted on said member and extend-

ing rearwardly therefrom, and weighting means common to said idler rolls and depending between said brackets.

3. In an attachment for carding machines for eliminating the subsequent processing of the sliver through a drawing frame, said attachment comprising a pair of horizontally disposed up-standing spaced parallel brackets substantially of U-form including upper and lower arms connected together at their rear ends by a bight, means for securing the lower arms of said brackets to the carding machine frame between a doffing cylinder and the calendar rolls, a front and a rear vertically disposed inner sidewise aligned bearing guides secured upon the rear portion of the upper arm of each of said brackets, front and rear upper bearings slidably mounted

in said guides, front and rear lower bearings mounted in said guides, front and rear idler rolls carried by said upper bearings, a feed roll carried by said lower front bearings, a drawing roll carried by said lower rear bearings, a vertical support secured upon the front portion of the upper arms of the said bracket, a rearwardly directed horizontally disposed trumpet secured to said vertical support, a supporting member arranged between said rear guides intermediate the ends of the latter and secured to such guides, a horizontally disposed condenser mounted on said member and extending rearwardly therefrom, and weighting means common to said idler roll depending between said guides and brackets.

ISAAC P. PELOQUIN.
